CLAIM

We claim the ornamental design for a articulating mounting unit for audio/visual devices or the like, as shown and described.

DESCRIPTION

FIG. 1 is a top perspective view of an articulating mounting unit for audio/visual devices or the like showing our new design;

FIG. 2 is a bottom perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines shown are for illustrative purposes only and form no part of the claimed design.
